(57) **CLAIM**

The ornamental design for a polishing cloth, as shown and described.

DESCRIPTION

FIG. 1 is a perspective view of a polishing cloth showing my new design;

FIG. 2 is a front elevational view thereof;

FIG. 3 is a rear elevational view thereof;

FIG. 4 is a right side elevational view with the left side being a mirror image thereof;

FIG. 5 is a top view thereof; and,

FIG. 6 is a bottom view thereof.

The broken line showing of the gripping means in FIGS. 1 and 5 is for illustrative purposes only, merely showing the type of gripping means that can be used, and forms no part of the claimed design.
